UNITED STATES PATENT OFFICE

154,835

DESIGN FOR A LAWN EDGER

Norman E. Bishop, Cleveland, Ohio

Application December 4, 1947, Serial No. 142,954

Term of patent 7 years

(Cl. D35—2)

To all whom it may concern:

Be it known that I, Norman E. Bishop, a citizen of the United States, residing at Cleveland, in the county of Cuyahoga and State of Ohio, have invented a new, original, and ornamental Design for Lawn Edgers, of which the following is a specification, reference being had to the accompanying drawing, forming part thereof.

Figure 1 is a top plan view of a lawn edger, showing my new design.

Figure 2 is a rear end view of the same with the handle detached.

Figure 3 is an enlarged side elevation of the same with a portion of the handle broken away.

I claim:

The ornamental design for a lawn edger, as shown.

NORMAN E. BISHOP.
